UNITED STATES PATENT OFFICE.

ROWLAND ROBINSON HAZARD, OF NEW YORK, N. Y.

MEANS OF ACCESS TO A NUMBER OF SURFACE, Elevated, OR UNDERGROUND RAILWAYS.

SPECIFICATION forming part of Letters Patent No. 413,942, dated October 29, 1889.

Application filed April 2, 1887. Serial No. 233,371. (No model.)

To all whom it may concern.

Be it known that I, ROWLAND ROBINSON HAZARD, a citizen of the United States, and a resident of New York, N. Y., have invented 5 a new and useful Improvement Relating to Means of Access to a Number of Surface, Elevated, or Underground Railways, as hereinafter fully described.

The object of this invention is to provide 10 access to trains in any one of a number of underground, surface, or elevated railways, or railway tunnels or structures so closely arranged in respect to each other as to leave insufficient space for platforms or means of 15 entrance and exit between them.

In the accompanying drawings, Figure 1 is 20 a transverse section of a station of an underground-railway structure, showing my invention. Fig. 2 is a modification thereof.

Hitherto in underground railways the several tracks have been arranged on approximate levels with landings or platforms at the side of the walks, respectively, or between them, and stairways leading to these platforms from the street, either directly or 25 through buildings. This arrangement of tracks and platforms between them on an approximate level requires lateral space for curves and turn-outs to admit the placing of 30 said platforms. In some instances it may become desirable to confine the tunnels or tracks within a narrow space, so as to preclude locating the platforms between the tracks. Provision must then be made for 35 access to more than one train at the same point or in the same station. To this end the tracks at the station are arranged on different planes.

Referring to the drawings, in Fig. 1 are 40 shown four tracks, the inner ones A A being on a higher plane than the outer ones B B. This location of the tracks may be brought about by a depression of the road-beds of the side tracks at the station to such a depth 45 as to bring the top of the trains on the side tracks slightly above the tracks of the inner roadway, as shown. A platform C is placed over each of the side tracks adjacent to the

inner tracks. The walls of the tunnels (if there be tunnel-walls on the line) are discontinued at the station, except that between the inner ones, as indicated at F, which is preferably retained. At one side of the lower tracks B is located a platform E, which is shown to be connected by a stairway D with 50 the upper platform C, but which may connect directly with the surface by a stairway, elevator, or other suitable means. A stairway G leads from platform C to the street or surface, or preferably to a house. In narrow 55 streets and localities where sufficient room is lacking access can thus be had to express and way trains by a double deck or platform station and limited lateral space utilized for a number of tunnels or accessible tracks. 60

In Fig. 2 is shown a modification, where the planes are reversed, the inner tracks A A being below and the outer ones B B above. In this instance the road-bed of the inner tracks is in a depression at the station and the 65 outer tracks are nearly on a level with the upper platform. The upper platform C' is narrower than C and the lower platform E' is as wide, extending beneath the side tracks and adjacent to the inner ones. The support 70 of the side track may be a metallic structure with space beneath for access to the inner tracks; or it may be solid with a masonry or other arch formed therein, under which the lower platform extends. The double 75 platform may be connected by a stairway D, as before, or directly with the surface or a building. The same principle is carried out here as in the arrangement in Fig. 1, the tracks being on different planes and accessible 80 by means of a double platform. 85

What I claim is—

1. In underground-railway stations, the combination of four adjacent tracks, of which the two outer ones are arranged in different 90 vertical and horizontal planes from the two inner ones, with platforms adjacent to each track, substantially as described.

2. An underground-railway station having tracks on different planes, the outer track 95 being depressed below the inner, and a land-

ing for the inner track extending over the outer one, and a second landing adjacent to the latter, substantially as shown and described.

5 3. In underground railways having tunnels arranged close together, a double-platform station with tracks on different planes, the inner tracks having an adjacent platform

which extends over the outer tracks, substantially as described.

In testimony whereof I have hereunto subscribed my name.

ROWLAND ROBINSON HAZARD.
